CLAIM

The ornamental design for “touch screen with graphical user interface”, as shown and described.

DESCRIPTION

FIG. 1 is a first image in a sequence for a touch screen with graphical user interface;

FIG. 2 is a second image in the sequence;
FIG. 3 is a third image in the sequence;
FIG. 4 is a fourth image in the sequence;
FIG. 5 is a fifth image in the sequence; and,
FIG. 6 is a sixth image in the sequence.

The appearance of the graphical user interface transitions sequentially between the images shown in FIGS. 1-6. The process by which, and the time during which, one image transitions to another image forms no part of the claimed design. The outermost broken line depicts a touch screen. The remainder of the broken lines depict aspects of the user interface of the touch screen. The broken lines form no part of the claimed design.

1 Claim, 6 Drawing Sheets
